UNITED STATES PATENT OFFICE.

JOSEPH D. WOOD, OF MURRYSVILLE, PENNSYLVANIA, ASSIGNOR TO WESTINGHOUSE ELECTRIC & MANUFACTURING COMPANY, A CORPORATION OF PENNSYLVANIA.

INTERLOCKING DEVICE.

Application filed June 10, 1922. Serial No. 567,492.

To all whom it may concern:

Be it known that I, JOSEPH D. WOOD, a citizen of the United States, and a resident of Murrysville, in the county of Westmoreland and State of Pennsylvania, have invented a new and useful Improvement in Interlocking Devices, of which the following is a specification.

My invention relates to mechanical interlocking devices that are adapted to insure the proper relative movements of a plurality of levers, such as are employed in connection with the operation of electric switches.

My invention is designed especially for use in connection with electric motors that require a relatively low voltage when being started to bring them up to, and a higher voltage to maintain them at, their normal running speeds.

One object of my invention is to provide a construction wherein the switch that controls the low-voltage circuit must be moved to closed position and then completely opened before the switch that controls the high-voltage circuit can be closed and wherein in each switch is held against closing movement while the other switch is in closed position.

Another object of my invention is to provide means whereby the switch that controls the high-voltage circuit cannot be moved to closed position except within a limited time after the low-voltage circuit has been opened.

Various types of apparatus have been designed to automatically provide for the proper sequence of operation, as between a starting switch and a running, or high-voltage switch, but difficulty has been experienced in designing a structure wherein provision is made to insure the closing of the running switch before the motor has lost the momentum set up therein through the operation of the starting switch.

I provide a construction wherein the running switch must be closed, if at all, at substantially the instant that the starting switch lever reaches its open position, and one wherein the use of springs, with the difficulties incident thereto, are avoided.

In the accompanying drawings,

Figure 1 is a view, partially in side elevation and partially in section, of apparatus embodying my invention,

Fig. 2 is a view thereof in rear elevation, Figs. 3 and 4 are side elevational views

showing the positions occupied by certain of the parts at various stages of their movements, and

Fig. 5 is a sectional view showing the position occupied by certain of the other parts at certain stages of their movements.

My invention is shown as applied to the operating mechanism of a circuit breaker and comprises a bracket 6 secured to a panel 7. A lever 8 is supported in the bracket 6 by a pin 9, and a lever 10 is supported thereon by a pin 11. I will designate the levers 8 and 10 as starting-switch levers and running-switch levers, respectively, the lever 8 being employed to start the motor under low voltage and the lever 10 being employed to impress high voltage on a motor that is not shown.

At its outer end, the lever 8 supports, through a pin 14, a lifting rod 15 that controls a switch or circuit breaker, not shown. The lever 10, through a pin 13, operates a lifting rod 16 of another switch or circuit breaker, not shown. It will be observed that the pins 14 and 13 extend inwardly for considerable distances.

A casting or interlock member 18 is suspended from the bracket 6 by a pin 19 and is provided with side portions 20 and 21 that are joined by a web portion 22. The portion 22 is provided with an opening 23 therethrough, and with a latch-engaging portion 22a, as shown more clearly in Fig. 5.

The side portion 21 of the casting 18 is provided with an arcuate slot, one wall 25 of which serves as a camming surface and the other wall of which is provided with an offset portion 26 that may engage the pin 14 to restrain upward movement thereof under certain conditions.

The side portion 20 of the casting 18 is provided with a camming surface 28 and a shoulder 29 that are engaged by a pin 13, under predetermined conditions. (Fig. 5.)

A latch 31 is pivoted at 32 to the bracket 6 and is provided with an upwardly extending portion 33. The outer end of the latch 31 serves, when in operative position, to engage the portion 22a of the casting 18.

The levers 8 and 10, the casting 18 and the latch 31 normally occupy the positions illustrated in Figs. 1 and 2, in which position the switches controlled by the levers 8 and 10 are in open position. In this position, the pin 14 of the lever 8 may move

freely in the slot of the side portion 21 of the casting 18, but the pin 13 of the lever 10 is locked against movement by the shoulder 29 of the side portion 20 (Fig. 5).

- 5 Upon movement of the lever 8 in a clockwise direction, to close its switch through the lifting rod 15, the pin 14 is carried upwardly into engagement with the extension 33 of the latch 31, as shown more clearly in
 10 Figs. 3 and 4. This disengages the interlocking member 18 from the latch 31 and permits such member to swing in a counter-clockwise direction by reason of gravity, until the inner wall of a recess 35 (Fig. 5)
 15 of the side portion 20 of the casting is in engagement with the pin 13. The upper wall of the recess 35 is of such shape that pressure upwardly by the pin 13 will not tend to move the member 18 to the position
 20 shown in Fig. 5 and thus permit the latch to fall when the pin 14 is moved away from the extension 33.
- This movement by the casting 18 carries the camming surface 25 into the path
 25 of the pin 14 so that, upon a rapid movement of the lever 8 in a counter-clockwise direction, a camming engagement takes place between the pin 14 and the wall 25 sufficient to swing the casting 18 in a clockwise direction past the position shown in
 30 Fig. 5 and release the pin 13 of the lever 10 from engagement with the shoulder 29. In this position, if the lever 10 be moved quickly in a clockwise direction, the pin
 35 13 carried thereby may pass upwardly along the camming surface 28 to close the switch that is controlled by the lifting rod 16. This movement carries the lower end of the interlocking member still further in a
 40 clockwise direction and brings the shoulder 26 of the side member 21 into the path of the pin 14 to prevent upward movement of such pin and thus insure that the starting switch which is actuated by the lifting rod
 45 15 cannot be closed until the lever 10 has been moved in a counter-clockwise direction to return the pin 13 and the lifting rod 16 to their lower, or open, positions. Upon
 50 downward movement of the pin 13, the interlock member 18 may swing back, under the action of gravity, to latched engagement with the latch 31, thus causing the lever 10 to be again latched in retracted position and the lever 8 be again released for movement to advanced position.

To secure certainty in its operation, the lever 10 is maintained under closing tension while the lever 8 is being retracted, so that it may be snapped to advanced position the instant the lever 8 has reached its open position. The contour of the engaging surface of the shoulder 26 is such that the upward pressure of the pin 13 does not seriously resist the movement of the casting 18 by the camming action above described.

The latch 31 also serves to hold the member 18 against movement, through force exerted by the pin 13 against the rounded surface of the shoulder 26 in case an attempt be made to operate the lever 10 out of its turn.

It will be observed that the latch 31 is of such contour that it permits the lug 22a to pass thereover freely, when moved rapidly in a clockwise direction, but will catch the lug 22a when the casting 18 swings back, in a counter-clockwise direction.

From the foregoing, it will be seen that the casting 18 is of such form that it prevents either of the switch levers 8 and 10 from being moved to closed position while the other lever is closed and that the lever 10 cannot be closed until the lever 8 has been first advanced and retracted. Furthermore, the lever 10 cannot be moved to closed position except at substantially the instant the lever 8 reaches its open or retracted position.

Various changes in detail and arrangement may be made without departing from the spirit and scope of the invention, as defined in the accompanying claims.

I claim as my invention:

1. The combination with a pair of levers, of an interlocking device therefor comprising a movable member having cam surfaces to be engaged upon the movement of said levers, said movable member being provided with stop members for preventing the operation of either lever when the other lever is in its operative position, and a latch member for securing said movable member in one position.

2. The combination with a pair of levers having members movable therewith, of means for preventing the operation of either of said levers when the other is in its operative position, said means comprising a movable element having cam surfaces coacting with said members to control the position of said element, and a latch member for securing said element in locking relation to one of said levers.

3. The combination with a pair of levers having members movable therewith, of means for preventing the operation of either of said levers when the other is in its operative position, said means comprising an interlocking member having slots therein to provide cam surfaces for coacting with said movable members to control the position of said interlocking member, and a latch member controlled by one of said levers for securing said interlocking member in locked relation to one of said levers.

4. The combination with a primary lever and a secondary lever, of an interlock member therefor provided with a locking portion for normally preventing advancement of the

secondary lever, a latch for holding the interlock member in said normal position, means carried by the primary lever for tripping the latch when the said lever is advanced and for moving the interlock member into released position with respect to the secondary lever when the primary lever is retracted, and means carried by the secondary lever for moving the secondary lever into locking relation with respect to the primary lever when the secondary lever is advanced.

5. The combination with a primary lever and a secondary lever, of an interlock member therefor provided with a locking portion for normally preventing advancement of the secondary lever and with camming surfaces, a latch for holding the interlocked member in said normal position, camming means carried by the primary lever for tripping the latch when the said lever is advanced and for moving the interlock member into released position with respect to the secondary lever when the primary lever is retracted, 20 and camming means carried by the secondary lever for moving the interlock member into locking relation with respect to primary lever when the secondary lever is advanced.

6. The combination with a pair of levers, 30 of an interlock device therefor comprising a movable locking member provided with stop members for preventing the advancement of either lever while the other lever is advanced, a latch for normally holding the locking member in locked relation to the one lever, and means effective during the movement of the other lever through a cycle, to trip the latch and to move the locking member to release 35 position with respect to the first named lever, and means carried by the first named lever for moving the locking member into locking relation with the other lever when said first named lever is advanced, the locking member moving to the said latched position, when the first mentioned lever is retracted.

ber to released position with respect to the first named lever.

7. The combination with a pair of levers, of an interlock device therefor comprising a movable locking member provided with stop members for preventing the advancement of either lever while the other lever is advanced, 45 a latch for normally holding the locking member in locked relation to the one lever, means effective during the movement of the other lever through a cycle, to trip the latch and to move the locking member to release position with respect to the first named lever, and means carried by the first named lever for moving the locking member into locking relation with the other lever when said first named lever is advanced.

8. The combination with a pair of levers, of an interlock device therefor comprising a locking member provided with stop members for preventing the advancement of either lever while the other lever is advanced, 60 a latch for normally holding the locking member in locked relation to the one lever, means effective during the movement of the other lever through a cycle, to trip the latch and to move the locking member to release 65 position with respect to the first named lever, and means carried by the first named lever for moving the locking member into locking relation with the other lever when the first mentioned lever is retracted.

In testimony whereof, I have hereunto subscribed my name this first day of June, 1922.

JOSEPH D. WOOD.
